UNITED STATES PATENT OFFICE.

STUART ARCHER WEISS, OF RICHMOND, VIRGINIA.

BACK AND HEAD REST.

SPECIFICATION forming part of Letters Patent No. 768,209, dated August 23, 1904.

Application filed December 1, 1903. Serial No. 183,344. (No model.)

To all whom it may concern:

Be it known that I, STUART ARCHER WEISS, a citizen of the United States, residing at Richmond, in the county of Henrico and State of Virginia, have invented certain new and useful Improvements in Back and Head Rests, of which the following is a specification.

My invention is a back and head rest and is designed for the use of the sick in private families and in hospitals, affording patients an easy, convenient, and comfortable back and head rest in lieu of pillows and other uncomfortable and inconvenient contrivances used for this purpose.

In the accompanying drawings, Figure 1 is a perspective view of my invention when set up for use. Fig. 2 is a vertical section of Fig. 1, cut on the line X X. Fig. 3 is a longitudinal section of my invention when the same is folded. Fig. 4 is an inside view of one of the arm-rests, part of the tray, and the means of holding the said tray to the arm. Fig. 5 is a sectional view of Fig. 4 on the line Y Y, the tray being left off. Fig. 6 is a perspective view of the arm-holders attached to one of the side beams of the web-frame. Fig. 7 is an inside view of one of the arm-rests, with means of attaching it to the arm-holders shown in Fig. 6. Fig. 8 is a perspective view of part of the beams, with a lock thereto attached. Fig. 9 is a perspective view of part of another beam, with the lock-bolt holder attached thereto. Fig. 10 is a perspective view showing one corner, part of a side beam, and part of an end beam of the web-frame and part of the prop-frame, together with a catch secured to the end beam of the web-frame. Fig. 11 is a sectional view of two of the prop-frames at the point where they are locked and a view of the lock locking the frame.

My invention is described as follows: It consists of three light but substantial rectangular frames averaging in length about three feet and in width two feet. The two first-mentioned frames 1 and 2 are hinged together at their front ends by a substantial hinge 4 in such a way that these two frames when shut fit close together and completely inclose the third or prop frame. Said frame or prop-

frame consists of three light frames *a*, *b*, and *c* and are horizontally hinged together by butt or strap hinges 5, the top frame *a* being hinged to the rear end of the web-frame 2 by a substantial hinge, said frames *a*, *b*, and *c* being adapted to fold up on themselves, thereby giving greater or less pitch to the web-frame. Thus when the frame *c* is folded back the lower end of frame *b* rests against the rear end of the base-frame 1, and when the frames *c* and *b* are folded back the lower end of frame *a* rests against the rear end of said frame 1. Thus in this position the web-frame is nearly on a horizontal line.

The prop-frame 3, consisting of the parts *a*, *b*, and *c*, is adapted to form a straight line and to be held in such position rigidly by locks 8, consisting of a lock-case 8', carrying a hinged lock-bolt 8", said lock-bolt having a hook 8' and a lock-bolt holder 8", said lock-case being secured to a cross-beam of one of the frames *a*, and the lock-bolt holder 8" being secured to the adjoining frame *b*. The frames *b* and *c* are held together by a similar device. The said prop-frame 3 is not quite so long or so wide as the base-frame 1 and the web-frame 2, and said base and web frames are provided with recesses 9 and 10 in their inner edges to accommodate and envelop said prop-frame 3, so that when the two frames 1 and 2 come together said prop-frame is completely hidden and protected.

The rear cross-beam 11 of the base-frame 1 is provided with a lock *d*, consisting of a case 12, carrying a lock-bolt 13, having on the free end of said bolt a hook 14. Said bolt is actuated by a spring 15. Secured to the cross-frame 16 of the frame *c* is a lock-bolt holder 17, which constitutes a part of the lock *d*, and when the prop-frame 3 is in position as shown in Fig. 2 it is locked in said position by the lock-bolt 13 entering into the lock-bolt holder 17. This lock-bolt 13 performs the additional function of locking the rear ends of frames 1 and 2 together by the hook 18, Fig. 10, entering the square perforation 19 in the lock-case 12, Fig. 8, the said bolt 13 catching over the hook 18, Fig. 10.

Secured to the two side beams of the web-frame 2 are slotted arm-holders 20. These

arm-holders consist of metal straps bent so that their two parts are at right angles one with the other, one part, 21, being secured against the edge of the beam and the other 5 part, 22, against the face of the beam. The parts 21 are each provided with a bayonet-slot, while the parts 22 are provided with bed-rail slots.

Adapted to fit and extend horizontally from 10 the front face of the web-frame 2 are arm-rests 23. These arm-rests are each secured to a right-angle piece 24, provided with lock-pins 25, adapted to enter into, slide down, and hold in said bayonet-slots and bed-rail 15 slots. These arm-rests 23 are attachable and detachable, either, with two motions. Detachably secured to these arm-rests is a tray 26. This tray is secured to the upper edges of a couple of beams 27. These beams are each 20 provided in their outer faces with a recess 28, and to the outer face of each beam is secured a spring-catch 29, provided each with a U-shaped recess bend 30, which may be forced back into the recesses 28. A spring-lock 25 holder 31 is secured one to the outer face of each of said arm-rests provided each with a catch-bar 32. To fix the tray in place, we take hold of it and thrust the beams 27 into the spring-lock holders 31 until the U-bend 30 passes the catch-bar 32, and to remove the tray we put the two index-fingers on the spring ends of the springs 29, press them down to the beams 27, and draw them out, and the tray is removed. Thus it is attached by one motion and detached by one motion.

The web-frame 2 is covered by a webbing 2 or other suitable material.

Though this invention is primarily intended for hospitals and sick-rooms, it may be used 40 for army purposes. By stretching out the three frames 1, 2, and 3, laying them on the ground, and spreading over them an oil-cloth of any kind the soldier, sick or well, may be kept from coming in contact with the cold 45 ground. By stretching out the three frames it may be used as a stretcher, because said parts are so hinged that when stretched out they become rigid on a straight line.

This invention may also be used as a seat 50 by simply turning the tray over on the arms, (see Fig. 1,) and it may also be used as a table by setting the frames 1 and 3 in a vertical position and the web-frame 2 in a horizontal position and bracing the same by any suitable 55 means.

Having described my invention, what I claim as new, and desire to secure by Letters Patent, is—

1. A back and head rest, consisting of a base-frame 1, provided with an internal recess 60 9; a web-frame 2, hinged to said base-frame at its front end, and provided with an internal recess 10; a web covering 2', stretched over the upper face of said web-frame; a prop-frame 3, consisting of three small frames, *a*, 65 *b* and *c*, hinged and locked together; the upper frame *a*, hinged to the rear end of said web-frame, and the lower end of frame *c*, adapted to rest on the rear end of said frame 1, substantially as shown and described, and 70 for the purposes set forth.

2. The combination of a rectangular base-frame 1, provided with internal recesses 9; a rectangular web-frame 2, hinged to said frame 1, at its front end, and provided with an internal recess 10; a web covering 2', stretched over the upper face of said web-frame; a prop-frame 3, consisting of three small frames, *a*, *b*, *c*, hinged and locked together; arm-rests 23, detachably secured to said web-frame, and 75 a tray detachably secured to said arm-rests, substantially as shown and described, and for the purposes set forth.

3. In a back and head rest, slotted right-angle arm-holders 20, provided with a bayonet-slot in one wing and a bed-rail slot in the other wing, secured to the side beams of the web-frame 2; arms 23, extending from a right-angle piece 24, and lock-pins 25, secured in 80 said right-angle piece, and adapted to catch in the slots of the lock-holders 20, substantially as shown and described and for the purposes set forth.

4. In combination with a back and head rest, arm-rests 23; spring-lock holders 31, secured to the outer faces of said arm-rests, each provided with a catch-bar 32; a tray 26, secured to two beams 27, each beam provided with a recess 28, in their outer faces, and spring-catches 29, each provided with a U-shaped 85 bend 30, adapted to rest in the recesses 28, substantially as shown and described and for the purposes set forth.

In testimony whereof I affix my signature in presence of two witnesses.

STUART ARCHER WEISS.
